ATTORNEY

UNITED STATES PATENT OFFICE

168,296

ASH TRAY

Littleton B. Gamby, Baltimore, Md.

Application March 19, 1952, Serial No. 18,965

Term of patent 3½ years

(Cl. D85—2)

To all whom it may concern:

Be it known that I, Littleton B. Gamby, a citizen of the United States, residing in the city of Baltimore and State of Maryland, have invented a new, original, and ornamental Design for an Ash Tray, of which the following is a specification, reference being had to the accompanying drawing, forming a part thereof.

Figure 1 is a top plan view of an ash tray showing my new design; and

Figure 2 is a cross-sectional view thereof taken on line 2—2 in Figure 1.

I claim:

The ornamental design for an ash tray, as shown.

LITTLETON B. GAMBY.
